WILHELM SIMONSSON, OF BROOKLYN, NEW YORK.

RETARDING DEVICE.

1,230,932.

Specification of Letters Patent. Patented June 26, 1917.

Application filed March 25, 1911, Serial No. 616,815. Renewed December 12, 1916. Serial No. 136,545.

To all whom it may concern:

Be it known that I, WILHELM SIMONSSON, a subject of the King of Sweden, and a resident of Brooklyn, in the city and State of New York, have invented certain Improvements in Retarding Devices, of which the following is a specification.

This invention relates to certain improvements in retarding devices, and more particularly in that class of such devices which are of the dash-pot type, and the object of the invention is to provide a retarding device of this general character of a simple and comparatively inexpensive nature, and of a strong, compact and durable construction, having certain features of novelty and improvement which are calculated to insure reliable and effective operation and use of the device for a long period of time without requiring repair or adjustment of its operative parts, and without excessive liability of deterioration or derangement of such parts from the accumulation of dust, hardened lubricant, etc.

The invention consists in certain novel features of the construction, and combinations and arrangements of the several parts of the improved retarding device, whereby certain important advantages are attained, and the device is rendered simpler, less expensive and more reliable and effective, and otherwise better adapted and more convenient for use, all as will be hereinafter fully set forth.

The novel features of the invention will be carefully defined in the claims.

In order that my invention may be the better understood I will now proceed to describe the same with reference to the accompanying drawings, wherein I have illustrated several forms of retarding device embodying my improvements and especially designed for use in connection with weighing scales and other instruments of precision, in which drawings—

Figure 1 is a sectional view taken centrally or axially through one form of the improved retarding device;

Fig. 2 is an enlarged sectional view taken transversely through the device shown in Fig. 1;

Fig. 3 is an enlarged fragmentary section showing certain features of construction to be hereinafter referred to;

Fig. 4 is an enlarged fragmentary section showing certain details of the pivotal sup-

port for one of the members of the improved retarding device;

Fig. 5 is an axial section somewhat similar to Fig. 1, but showing a slightly different 60 deformation of the improved retarding device;

Fig. 6 is another axial section illustrating another formation of the retarding device comprised within the present invention; and 65

Fig. 7 is a detached detail view showing a feature of construction to be hereinafter described.

The retarding device shown in Figs. 1 to 4, inclusive, is of the well known dash-pot 70 type having a cup or cylinder member 1 provided with an air chamber 2 wherein is housed the piston member 3, which is held stationary upon the frame 4, or other support, by means of a screw or bolt 5 which is passed centrally through said piston and through an apertured part of the frame member whereon the piston rests, and carries a nut 6 at its lower end by means of which the piston may be locked securely in 75 place against accidental movement upon the frame.

The cup or cylinder member 1, as shown in these views, is provided with a central upturned arm or projection 7, apertured in 85 its upper end, as shown at 8, for the passage of a knife edge 9 the extremities whereof are mounted in the spaced forks of a link 10 or equivalent part which is premised to be coupled with or to form a part of one 90 of the moving elements of a weighing scale or other instrument in connection where-with the improved retarding device is applied for use so that reciprocatory movement shall be applied to move the cup or 95 cylinder member vertically with relation to the rigidly positioned piston member during the operation of such instrument.

As clearly shown in Figs. 1, 2 and 3, the piston member 3 is made slightly less in diameter than the diameter of the internal air chamber 2 of the cup or cylinder member of the device, and in assembling the parts, the piston member is rigidly positioned in axial alinement with the direction of movement 100 of the reciprocating cup or cylinder member, whereby the difference in the diameters of the parts affords an absolute space or clearance 11 between said members and surrounding or encircling the margin of the 110 piston member, so as to provide a narrow or contracted vent or passage for the flow of

air into or out of the air chamber 2 of said cut or cylinder member when the cup or cylinder is moved relatively to the piston during the operation of the improved retarding device.

By this construction and arrangement of the parts I am permitted to eliminate or minimize the effects of friction in the operation of the retarding device, and therefore 10 materially to increase the accuracy and sensitiveness of the weighing scale or other instrument in connection with which the dash-pot is employed, it being evident that the absolute spacing of the members 1 and 3 15 in this manner permits of avoiding frictional contact between them and assures the greatest freedom of movement of one member relatively to the other, at the same time dispensing altogether with the use of flexible packing commonly provided for closing the joint between the piston and cylinder, and also dispensing with the special vent or duct commonly provided for the entry or escape of air into or from the cylinder, 20 whose functions are performed by the space or passage 11 in the device embodying my improvements.

In the drawings I have shown the aperture 12 of the frame member 4 through 30 which the bolt or screw 5 is passed of a diameter slightly greater than that of such bolt or screw, so as to facilitate a certain lateral adjustment of the piston member relatively to the frame member 4 when said bolt or screw 5 is loosened, to the end that the piston member may be readily and accurately alined with the axis of the cup or cylinder member during the assembling of the parts, so that the annular space or clearance 35 11 may be maintained unobstructed, and frictional contact and binding of the parts may be avoided. The pivotal support or suspension afforded by the knife edge 9 for the cup or cylinder member 1 also permits a 40 certain extent of free swinging movement of said member laterally with relation to the fixedly positioned piston member 3, whereby sticking or binding of the parts is avoided, and the provision for lateral movement 45 of the suspended reciprocating member thus afforded is of particular advantage where the instruments to which my improvements are applied are subjected to sudden shocks or vibrations which, if both members of the 50 55 retarding device were prevented from lateral movement, would give rise to undesirable friction and binding of the parts.

In the construction of the improved retarding device, and more especially when 60 the same is designed for use in connection with weighing scales and similar instruments of precision where great accuracy and sensitiveness is desirable, I prefer to proportion the parts in such a manner that the air chamber 2 of the cup or cylinder 1 has a ca-

pacity calculated with respect to the area of the annular space or passage 11, the pressure tending to move one of the members relatively to the other, and the interval of time during which the retarding action is 70 desired to be exerted, and since, in many of the instruments of precision to which my invention is applicable, the elements whose movement is to be checked or retarded have but short travel, I find it preferable in the 75 construction of the retarding devices for application to such instruments, to give to the cylinder and piston a diameter of comparatively great width with respect to the travel of one member relatively to the other, and 80 to form the air chamber of very small cubical capacity, as compared with its diameter and the area of the piston, so that in the operation of the device, the piston will rapidly produce a very high degree of compression of the air in the air chamber, and afford an extremely quick retarding action, 85 irrespective of the fact that the margin of the piston is spaced from the wall of the cylinder.

I have also shown the piston member 3 provided upon its upper surface with an elevated edge wall or rim 14, within which a circular cavity or chamber 15 is provided which affords an air cushioning means operating upon extreme downward movement of the cylinder or cup 1, materially to relieve the shock which would be imparted to the moving elements of the weighing scale or other instrument to which the device is applied for use, by the impact of the top wall of said cup or cylinder upon the top surface of the piston.

As shown in the drawings, the cup or cylinder 1 is closed at its top against the entry of dust and the like which would tend by its accumulation within the chamber 2, to interfere with the desirable freedom of movement of the members, and said cup or cylinder member is also open at its base to afford access to said chamber 2, but I do not desire to be understood as limiting myself in these particulars. Where the open bottom is provided in the cylinder or cup, however, I have sometimes found it desirable to extend an auxiliary flexible closure over the same, as clearly shown at 16 in Fig. 1, so as further to guard against the entry of dust and the like. As shown in this figure, the auxiliary closure is in the form of a cloth 110 or other flexible diaphragm, having its central part affixed as indicated at 17 between the piston and frame member 4, and having its edge portions clamped between the lower edge of the cylinder wall and a clamping 115 ring or member 18 held in position by screws 19.

I have also shown the marginal or perimetral surface of the piston member 3 as made convex in Figs. 1 and 3, the same being 120

- provided with a parti-spherical surface 19, struck with a radius 20 from the axis of the piston at a point midway of the width of said marginal or edge surface of the piston, 5 whereby it will be evident that the piston is adapted to accommodate itself automatically to all ordinary rocking or pivotal movements of the cylinder to the end that a substantially uniform area of the space or 10 passage 11 may be maintained at all times and binding or clogging of the piston within the cylinder further guarded against. This formation of the piston permits the space or passage 11 to be made of comparatively narrow width without undue liability of its becoming occluded. 15
- I have also shown the marginal or perimetral surface of said piston 3 provided with an annular groove or channel 21, enclosing 20 circling said piston midway of the width of its said parti-spherical surface 19, this encircling groove or channel 21 affording an effective and reliable air packing which impedes the flow of air through the space or 25 passage 11 during the operation of the improved retarding device, and permits of making said space or clearance of greater area than would otherwise be possible without lessening the retarding action exerted 30 by the device.

In Fig. 5 I have shown an embodiment of my improvement very similar to that above described, except that the forms of the piston and cylinder members are slightly 35 modified, and the lower edge portion of the cylinder wall has an inwardly directed annular part whose face presented to the piston has such a convexity, as shown at 19^a, as is calculated to compensate for the rocking or pivotal movement of the cylinder to prevent occlusion of the space or passage 11 around the piston. This convex surface 19^a is also centrally grooved or channelled, as shown at 21^a for impeding the flow of 40 air through said space or passage 11.

In Fig. 6 I have shown another embodiment of my improved retarding device which is in some respects alternative to that shown in Fig. 1, particularly in that the 45 piston is suspended and moves within the cylinder which is held stationary upon the frame and capable of lateral adjustment for alining it with the inclosed piston.

In this form of the device, the cylinder 1^a 50 is held stationary within a chamber 22 of the frame, and has a conical top wall provided with a flattened surface 23 engaged by a pendent skirt or projection 24 of the frame, which holds said cylinder in place while 55 permitting the same to be adjusted laterally of chamber 22 by means of adjusting screws 25. The apex of the cylinder has a central boss 26, wherein a graphite or other anti-friction bushing 27 is retained by means of 60 a screw 28 in such position that the draft 65

rod or link 30 which couples the piston with the mechanism to be retarded may play through the bore of said bushing, there being sufficient clearance between the bushing and said rod or link to prevent undue friction at 70 this point in the operation of the device. Three of the screws 25 are shown herein so disposed as to permit adjustment of the cylinder in all directions.

The cylinder is open at its base for the 75 passage of the lower end of the draft rod or link 30, which latter is thereby adapted for connection with suitable actuating means as, for example, a scale platform or other load support. The central or intermediate part 80 of said draft rod 30 has, within the chamber of said cylinder, spaced collars or enlargements 32, 32 between which is loosely mounted the central part of the conical top 33 of the bell-shaped piston member 3^a, the 85 structure and arrangement of the parts being such that said piston member is balanced or suspended for free pivotal or rocking movement upon its connection with rod 30 between said collars, in order that it may swing 90 or move laterally to conform with the walls of the chamber of the cylinder during its vertical movement therein, and thereby compensate for vibration and inaccuracies in the positioning of the parts. 95

The connections afforded by the upper and lower ends of the draft rod 30 between the movable member of the retarding device, and the mechanism to be retarded, and between said member and the actuating means 100 being alined axially with each other it will be apparent, however, that the lateral play of one member of the retarding device relatively to the other member is reduced to a minimum, in order that liability of contact 105 or friction of the piston upon the cylinder wall may be eliminated to as great an extent as possible.

With regard to the annular space or passage 11 for the flow of air during movement 110 of the piston, and the air packing groove or channel and semi-spherical surface at the margin of the piston, the structure of the device shown in Fig. 6 is similar to that shown in Fig. 1, excepting that said semi-spherical surface and groove or channel are produced in a graphite or other anti-friction ring 34 which is secured to and projects from the margin of the piston member in position 115 for contact upon the cylinder walls to reduce friction incident to excessive rocking or lateral movement of the piston. In the structure shown, the graphite ring 34 is constructed in a plurality of segments as indicated in Fig. 7 and these segments after having been plated with copper or the like are secured in connected relation upon the piston member by means of solder as clearly indicated at 35. 120

From the above description of the inven- 130

tion it will be seen that the improved retarding device constructed in accordance therewith is of an extremely simple and comparatively inexpensive nature, and is particularly well adapted for use by reason of the efficiency and reliability of its operation, and of the absence of friction and non-liability of deterioration which renders the device especially well suited for use in connection with weighing scales and other instruments of precision where accuracy of movement and durability are prime considerations, and friction is to be avoided in the greatest measure possible, and it will also be obvious from the above description that the device is susceptible of some modification without material departure from the principles and spirit of the invention, and for this reason I do not desire to be understood as limiting myself to the precise formation and arrangement of the several parts of the device herein set forth in carrying out my invention in practice.

Having thus described my invention, what I claim and desire to secure by Letters Patent is:

1. A dash pot retarding device having two relatively movable members, one of which is a cylinder having an air chamber open at one end of the cylinder, and the other of which is a piston within said chamber having its margin separated from the wall of the cylinder by a space which lessens friction between the members and affords an air passage between said air chamber and the open end of the cylinder and adapted for the flow of air when one member is moved relatively to the other, and a closure extended over the open end of the air chamber and adapted to exclude dust and the like and capable of flexure to accommodate relative movement of the members.

2. A dash pot retarding device having two relatively movable members, one of which is a cylinder having an air chamber closed at its upper end for the exclusion of dust, and open at its lower end, and the other of which is a piston housed within said chamber having its margin separated from the wall of the cylinder by a space which lessens friction between the members and affords an air passage having communication with said air chamber and is adapted for the flow of air when one member is moved relatively to the other, a support having connection with the piston and extended through the open lower end of the air chamber, and a closure for said lower end of the air chamber through which said support is passed having its margins connected with the cylinder wall and capable of flexure to accommodate relative movement of the members.

3. A retarding device including two relatively movable members, one of which is

supported for rocking movement relatively to the other, one of said members being a cylinder having an air chamber, and the other member being a piston housed in said cylinder and adapted to traverse the air chamber when one member is moved relatively to the other, said piston having its margins separated from the wall of the air chamber to afford a space which avoids friction and affords a passage for the escape of the contained air, and being of very large area as compared with the stroke of the movable member and with the cubic capacity of the air chamber, and operable upon movement of one member relatively to the other, to produce with great rapidity a high degree of compression of the air within said chamber.

4. A dash-pot retarding device having two relatively movable members, one of which is a cylinder provided with an air chamber and the other of which is a piston housed within said chamber, and a pivotal support for one of the members affording lateral movement thereof during travel of the piston within said chamber to insure alinement of the members during such travel, the piston having its margin provided with a parti-spherical surface concentric with the pivotal axis of said support, and spaced from the cylinder wall to afford clearance between said members and an air passage communicating with said air chamber and adapted for the flow of air during movement of one member relatively to the other.

5. A retarding device including two members, one of which is movable relatively to the other, one of said members being a cylinder provided with a shallow air chamber of large diameter as compared with the stroke of the movable member, and the other of said members being a piston adapted, when one member is moved relatively to the other, to traverse said air chamber of the cylinder, said piston having a diameter less than that of the air chamber to afford an annular air passage between its periphery and the cylinder wall adapted to avoid contact of the piston on said wall and provide for the entry and discharge of air into and from the air chamber, and of small area as compared with that of the piston, calculated to retard the flow of air into and from said chamber and to produce therein with great rapidity a high degree of compression when the movable member of the device is actuated.

6. A retarding device including two members, one of which is movable relatively to the other, one of the members being a cylinder provided with a shallow air chamber closed at its top but open at its base end of large diameter as compared with the stroke of the movable member, and the other mem-

- ber being a piston adapted, when one member is moved relatively to the other, to traverse said chamber of the cylinder and having a diameter less than that of said chamber to afford an annular air passage between its periphery and the cylinder wall adapted to avoid contact of the piston on said wall and to provide for the entry and discharge of air into and from the air chamber, said annular passage being of small area as compared with that of the piston, and calculated to retard the flow of air into and from said chamber and to produce therein with great rapidity a high degree of compression when the movable member of the device is actuated.
7. A retarding device including two members, one of which is movable relatively to the other, one of the members being a cylinder provided with an air chamber of large diameter as compared with the stroke of the movable member, and the other member being a piston adapted, when one member is moved relatively to the other, to traverse said chamber of the cylinder and having a diameter less than that of said chamber to afford an annular air passage between its periphery and the cylinder wall for the entry and discharge of air into and from said air chamber and of small area as compared with that of said piston, calculated to retard the flow of air into and from said chamber and to produce therein with great rapidity a high degree of compression when the movable member of the device is actuated, and parts extended oppositely from the movable member, whereon said member is loosely supported, and adapted for connection, respectively, with an actuating means, and with a mechanism to be retarded.
8. A retarding device including two members, one of which is movable relatively to the other, one of the members being a cylinder provided with an air chamber of large diameter as compared with the stroke of the movable member, and the other member being a piston adapted, when one member is moved relatively to the other, to traverse said chamber of the cylinder and having a diameter less than that of said chamber to afford an annular air passage between its periphery and the cylinder wall for the entry and discharge of air into and from said air chamber and of small area as compared with that of said piston, calculated to retard the flow of air into and from said member and to produce therein with great rapidity a high degree of compression when the movable member of the device is actuated, and parts extended oppositely from the movable member, whereon said member is loosely supported, and adapted for connection, respectively, with an actuating means, and with a mechanism to be retarded.

In witness whereof I have hereunto signed my name this 6th day of March 1911, in the presence of two subscribing witnesses.

WILHELM SIMONSSON.
